UNITED STATES PATENT OFFICE.

ALLAN A. ADAMSON, OF BROOKLYN, NEW YORK, AND WILLIAM F. GRUPE, OF HUDSON HEIGHTS, NEW JERSEY.

SCORING MACHINE.

Application filed February 21, 1919. Serial No. 278,418.

To all whom it may concern:

Be it known that we, ALLAN A. ADAMSON and WILLIAM F. GRUPE, citizens of the United States of America, respectively, residing at Brooklyn, county of Kings, State of New York, and Hudson Heights, county of Bergen, State of New Jersey, have invented certain new and useful Improvements in Scoring Machines, of which the following is a specification.

This invention relates to scoring machines and particularly for scoring strips of paper board or equivalent.

More particularly, the invention relates to a scoring mechanism constructed to score a strip of paper board, or equivalent, supplied from a reel of paper board, or otherwise of indefinite length.

The invention comprises generally means for supplying a strip of paper board, means for grinding or otherwise scoring the paper board at the desired locations corresponding to the corners or other points of bend or deflection and means for controlling the advance of the strip of paper board relative to such scoring means for effecting the required scorings at the required locations. In the most preferred forms of the invention, the scoring means is of the continuously operating type, and adjustably mounted to provide for adjustment of the depth of scoring and to compensate for reduced diameter of the scoring device after redressing. In such preferred forms of the invention, the supplied strip of paper board is moved or flexed into and out of contact with the scoring device, by a movable support comprising faces arranged at an angle to one another and adapted to successively receive and support successive portions of the strip to effect mutual contact between the scoring device and the strip at the desired locations, corresponding to the corners or bends of the resultant box, or similar article.

The invention is particularly advantageous for continuously feeding and advancing the strip.

In the form of the invention set forth in detail hereinafter, the scoring machine is a unit designed for the manufacture of necked cigarette boxes and is arranged for the simultaneous treatment of strips of paper board corresponding respectively to the

cover rim, neck and tray rim, whereby the three strips supplied from three reels of paper board are subjected to the same temperature and humidity conditions during the treatment. However, it will be apparent that the invention is also applicable for scoring a single strip of paper board or two or other number of strips, simultaneously or non-simultaneously.

Further features and objects of the invention will be more fully understood from the following description and the accompanying drawings, in which—

Fig. 1 is a side elevation of a scoring mechanism comprising our invention;

Fig. 2 is an end elevation of Fig. 1, as viewed from the right;

Fig. 3 is a top plan view, with certain parts being removed and other parts shown in horizontal section;

Fig. 4 is a detail side elevation of an intermittent control of the feed of the strips of paper board; and

Fig. 5 is a detail side elevation of a modified form of feed control, showing a continuous feed of the strips of paper board.

Referring to the drawings, the scoring mechanism as shown comprises the outer fixed frame members 1, 2 connected together in spaced relation by the tie rods 3, and the inner, transverse frame 4, vertically adjustable with respect to the frame members 1, 2, by means of the slots 5 and clamping bolts 5^a. The scoring machine as shown, is constructed as a unit to be clamped at the front end of a unit devised by us for producing simultaneously, i. e., under the same temperature and humidity the cover, neck and tray parts of a so-called cigarette box, i. e., a necked paper box, and embodying certain principles of treatment, as fully set forth in our copending application Serial No. 134,306, filed December 1, 1916, entitled Method of making boxes. The strip producing machine or unit, known by us as the "strip producer" is set forth in our copending application Serial No. 279,486, filed Feb. 27, 1919, and entitled "Paper box machine."

The treatments of the three strips of paper board corresponding to the cover rim, neck and tray rim, in the order named as viewed from left to right in Fig. 2, are generally similar, and accordingly the detail

construction and operation of the three sets of corresponding machine parts are herein-after described by particular reference to the set of machine parts for treatment of the 5 paper board to form the cover rim, excepting where special reference is made to the other two sets of machine parts.

The indefinite length of strip 6 of paper board is supplied from a roll or reel, suitably mounted on any approved individual 10 mount or support (not shown). The strip 6 is threaded on the guide 7, having the lateral guide flanges 8, thence under and in contact with the under face 9 of the shaft 10. The 15 guides 7 are mounted on the common shaft 11, adjustably positioned in the end frames 1, 2, by set screws, as shown, or in any other approved manner.

The strip 6 is then threaded between the 20 grinder 12 and the rotatable support 13, arranged and coacting as described more fully hereinafter, to effect the scoring of the strip to the desired extent or depth and at the desired locations corresponding to the corners 25 or bends of the resulting article. After the scoring treatment, the strip 6 passes under the brush 14, or equivalent, for removing the grindings from the strip.

After passage of each strip 6 past its 30 brush 14, the scored strips indicated at 15, 16, 17, representing respectively the strips corresponding to the cover rim, neck and tray rim, proceed for further treatment to the machine for producing the finished strip, 35 which last named machine is set forth and claimed in our copending application Serial No. 279,486, filed Feb. 27, 1919, and entitled Paper box machine.

Such strip producing machine embodies 40 means for advancing and keeping taut each strip, thereby controlling the advance of the strip through the scoring unit.

Each scoring device 12 shown as a grinder, is fixedly mounted on a hollow 45 shaft 18, to which is also fixed the gear 19. Through the hollow shaft 18 is passed the stud 20, having at one end the washer 21 and nut 22, and its other end supported in the adjustable box 23, shown as slidable 50 within the slotted arms 24, depending from the transverse frame 4. Each box 23 is provided with the adjusting stem 25, and is threaded at its upper end 26, adapted to receive the lock nut 27. The connection between each stem 25 and its box 23 is preferably effected by the provision of the 55 groove 34 receiving the set screw 35 passing through a suitable opening 36 in the box 23. The frame 4 is provided above the 60 respective depending arms 24 with the hubs 28 each having an upper face adapted to be engaged by a lock nut 27, whereby the position of the stem 25 and accordingly the scoring grinder wheel 12, is determined. 65 Each stem 25 may be provided with the

knurled head 29 to facilitate accurate adjustment of the position of the stem 25.

The gears 19 are driven by the respective gears 30 mounted on the common shaft 31, having bearings in the opposite arms of 70 the inner frame 4, and provided with the sprocket 32 receiving the chain 33. The chain 33 may be driven in the direction of the indicating arrow 37, to drive the grinders 12 clockwise, as viewed in Fig. 1. 75

In the arrangement shown in the drawings, the control of the feed of the strip into and out of contact with the scoring device, is effected by the provision of the support 13 for the strip adapted to flex or otherwise 80 move the strip 6 into and out of contact with the grinding wheel 12. Each movable support 13 is shown provided with four faces 41, 42, 43, 44 adapted to successively receive the strip 6 in the order named, being 85 rotatably mounted on the shaft 45 and rotated in the direction of the arrow 46, see Fig. 1. Upon rotation of the support 13 its successive corners 47, 48, 49, 50 in the order named cause the strip 6 to be raised 90 into contact with the scoring grinder 12, the said faces 41, 42, 43, 44 cooperating to permit the strip 6 to drop out of contact with the scoring grinder 12 as the movable support 13 is rotated. 95

In the form of the invention shown in Figs. 1, 2, 3 and 4, the rotation of the shaft 45, on which the three movable supports 13 are mounted, is under intermittent control, whereas the control indicated in Fig. 5 is of 100 the continuous type.

To effect the intermittent control, the shaft 45 is provided with the driving gear 51, loosely mounted thereon, meshing with the driving segment 52 pivotally mounted on the 105 stud 53 carried by the inner frame 4. The segment 52 is actuated by the driving arm 54 controlled and operated by any suitable driving mechanism and specifically by an eccentric arm controlled by the main shaft of 110 the strip producer, as set forth and described in our copending application Serial Number 279,486, aforesaid.

The connection between the gear 51 and the shaft 45 is of the ratchet type for effecting actuation of the shaft 45 upon clockwise rotation of the driving segment 52, as appears in Fig. 4, for which purpose the gear 51 is provided with the laterally extending plate 55, pivotally carrying the spring-pressed pawl 56 coacting with the notch 57 of the one-toothed ratchet 58 fixed on the shaft 45. Upon completion of the rotation of the strip supports 13 and the attainment of the end of the actuating stroke of the segment 52, the shaft 45 of the strip supports 13, is locked by the pawl 59, mounted on the stud 60, carried by the transverse frame 4, said pawl 59 being controlled by its spring 61 and its roller 62 in turn controlled by the 130

cam 63 fixed on the shaft 45. The cam 63 is provided with the notch 64, whereby upon entry of the roller 62 therein, the pawl 59 is forced by its spring 61 to seat in the V-
5 notch 65 of the locking disk 66, thereby locking the shaft 45 against displacement in either direction. Such period of locking ensues during the period of return movement of the segment 52 to re-engage the pawl 56
10 with the notch 57.

It will be noted that in the intermittent drive the rotation of each form 13 is counter to that of its scoring grinder wheel 12, thereby permitting the unidirectional actuation of
15 such intermittent drive to be utilized, and attain accurate registration of the scored portions of the strip. Such intermittent actuation of the forms 13 is adapted to the intermittent feed of the strip producer, such
20 as shown in our copending application Serial No. 279,486, as aforesaid.

For continuous actuation of the forms 13, the shaft 45, as shown in Fig. 5, is provided with the sprocket 67, fixed thereto, and
25 driven by the chain 68, in turn driven by suitable driving gearing on the cam shaft of the "strip producer".

It will be noted that by adjustment of the respective stems 25 of the scoring means 12,
30 the depth of scoring is determined. The angle of address or presentation of the strip with respect to the scoring means is determined by adjustment of the transverse frame 4 vertically with respect to the end frames
35 1, 2, by means of the slots 5 and lock bolts 5^a, whereby the position of scoring of the strip is regulated in reference to the fixed line of feed passing through the under surface of the front shaft 10. The rear shaft 69 corre-
40 sponds to the front shaft 10, and also serves to support the idler sprocket 70. Incident to wear of the grinding wheels 12 and redressing, the adjustment of the stems 25 compensates for the reduced diameter of the
45 effective grinding surface. It will be noted that whereas the gears 30, respectively driving the driven gears 19, of the sets of scoring devices, may be mounted in stationary bearings in the end frames 1, 2, the clearances af-
50 fforded by the teeth of each set of driving and driven gears, permits considerable latitude of adjusted position of each individual gear 19 relative to its driving gear 30.

The intermittent form of the invention, as
55 shown, attains a period of rest only at a determined stage of operation, namely, corresponding to the location of a length of a strip where it is severed in the "strip producer" the other scorings being performed
60 while the strip is being continuously advanced, similarly as is continuously performed in our form of continuous feed.

Whereas we have described our invention by reference to specific forms thereof, it will
65 be understood that many changes and modi-

fications may be made without departing from the spirit of the invention.

We claim.

1. The combination of a scoring device, stationary means of angular cross section 70 for mounting said scoring device, means for rotating said scoring device, rotary means for supporting a strip of paper board and means for rotating said supporting means.

2. The combination of a rotatable scoring 75 means fixed bearings for said scoring means, rotatable means of angular cross section for supporting a strip of paper board and fixed bearings for said rotatable supporting means.

3. In a scoring mechanism, a scoring wheel, means for supporting against said scoring wheel, a strip of paper board comprising a plurality of substantially flat face portions adapted to receive said strip on said 85 respective faces, said face portions being disposed at an angle to one another and means for rotating said supporting means.

4. In a scoring mechanism, a scoring wheel, means for supporting against said 90 scoring wheel, a strip of paper board comprising a plurality of substantially flat face portions adapted to receive said strip on said respective faces, said face portions being disposed at an angle to one another and means 95 for rotating said supporting means.

5. The combination with a plurality of means for individually mounting rolls of paper board, of a plurality of individual scoring means, common means for driving 100 said scoring means, individual means for intermittently moving the supplied strips into and out of contact with said individual scoring means respectively and common means for actuating said individual moving means. 105

6. The combination with individual means for mounting a plurality of rolls of paper board, of individual scoring means, common means for operating said individual scoring means, individual means for adjustably positioning said scoring means, means for individually supporting the respective strips of paper board and means for intermittently moving said individual supporting means to move the respective strips of paper board 115 into and out of contact with said scoring means respectively.

7. The combination with individual means for mounting a plurality of rolls of paper board, of individual scoring means, common 120 means for operating said individual scoring means, individual means for adjustably positioning said scoring means, means for individually supporting the respective strips of paper board and common means for intermittently moving said individual supporting means to move the respective strips of paper board into and out of contact with said scoring means respectively.

8. The combination of a plurality of rota- 130

table scoring means, common means for mounting said scoring means, common means for rotating said scoring means, individual means for supporting a plurality of strips of paper board on said supporting means comprising a plurality of face portions disposed at an angle to one another and common

means for mounting said individual supporting means.

In testimony whereof we have signed this 10
specification this 15th day of February 1919.

ALLAN A. ADAMSON.
WILLIAM F. GRUPE.
